UNITED STATES PATENT OFFICE.

WILLIAM F. OLIN, OF CHICAGO, ILLINOIS, ASSIGNOR TO HIMSELF AND
WILLIAM DEERING, OF SAME PLACE.

HARVESTER.

SPECIFICATION forming part of Letters Patent No. 309,795, dated December 23, 1884.

Application filed May 26, 1882. (No model.)

To all whom it may concern:

Be it known that I, WILLIAM F. OLIN, residing at Chicago, in the county of Cook and State of Illinois, and a citizen of the United States, have invented a new and useful Improvement in Adjusting the Delivery of the Grain to a Self-Binder, of which the following is a full description, reference being had to the accompanying drawings, in which—

10 Figure 1 is a plan view showing the arrangement of the carrying-frame for the binder and the frame for the grain-delivery canvas or carrier; Fig. 2, an under side view with the platform-frame broken off; Fig. 3, a side elevation; Fig. 4, a cross-section through the binder and platform-frame, with the side piece of the frame broken off; Fig. 5, a cross-section of the sliding shaft from which the sickle is driven.

15 The binding of grain by a self-binder is attended with one difficulty arising from the varying length of grain, and that is properly encompassing the bundle with the band at or near the center, to obviate which it has been customary to make the binder adjustable, so as to change its position in relation to the delivery of the grain and bring the binder-arm in position to encompass the bundle at or near its center, and although this works successfully and gives general satisfaction, 20 still it is attended with more or less difficulty, owing to the manner in which it is necessary to locate and support the binder in order to have it adjustable.

25 The object of this invention is to attain the result of binding the grain at or near the center of the bundle without changing the location of the binder; and its nature consists in providing a main supporting-frame on which the binder and other appliances are carried, 30 and connecting therewith a secondary or platform frame carrying the sickle and grain-delivery canvas or carrier, and which can be adjusted bodily fore and aft on the main or binder frame to change the delivery of the grain 35 to the binder, all as hereinafter particularly described, and then specified in the claims.

40 In the drawings a complete machine is not shown, but only so much as is necessary to illustrate the invention.

45 A represents the main or binder frame, 50 which may be made of side pieces, *aa*, and end pieces, *a'a'*, with an intermediate piece, *a²*, running from end piece to end piece, or in any other suitable manner adapted to receive and support the binder mechanism, the main and 55 drive wheel, and devices connected therewith and operated therefrom for working the sickle and grain-delivery devices.

60 B is the platform-frame, which may be made of end pieces *b b*, with side pieces *b' b'*, and an intermediate piece, *b²*, running from end piece to end piece, one of the pieces *b'* being in line with the outer side piece of the main frame, and the piece *b²* located so as to be in line with the inner side piece of the main or 65 binder frame, or in any other suitable manner that will bring the parts in such relative position as to enable an attachment to be made with the main or binder frame, and form a frame capable of receiving the delivery-canvas and supporting the sickle. The grain or 70 the outer end (adjacent to the standing grain) of this platform is provided with a divider, either attached to the end piece *b'* or forming a part thereof.

75 C are clasps, made of wrought metal or other suitable material, and formed to extend over the side pieces of the main or binder frame and to be attached to the inner side piece *b'* and the intermediate piece, *b²*, of the platform-frame by bolts, or otherwise connecting the platform-frame to the main frame, so that it can slide back and forth thereon. This attachment of the platform-frame and the main or binder frame could be made in some other 80 manner than by means of the clasp C, shown, and, if desired, anti-friction rollers might be provided between the side pieces of the main or binder frame and the side pieces *b'* and *b²* of the platform-frame, which are in line therewith, to facilitate the movement of the platform-frame on the binder-frame.

85 D is a receiving-table onto which the grain is delivered from the platform by the carrier to be bound, the table having a slot or opening, *c*, for the passage of the binder-arm.

90 E is a rotating shaft supported in a bracket or arm, *E'*, and carrying at its rear end a bind-

er or cord arm, *d*, and actuated by a sprocket-wheel, *e*, by means of a chain and connecting devices from the main or drive wheel. The actuating devices are not shown, neither is the 5 binder-arm and its support carried out in detail, as they may be of any of the well-known and usual forms of construction and arrangement, operating in the usual manner to encompass the bundle with the binding-cord and 10 carry the cord to the tying devices, which latter also are not shown, but are located beneath the binding-table *D* in any usual and well-known manner.

F is a frame having side pieces and a top 15 or horizontal piece, the lower ends of the side pieces being attached, respectively, to the outer side piece *a* of the binder-frame and intermediate piece, *a*², with the ends of each side extending below such pieces. As shown, the 20 inner side piece of this frame is extended up, so as to form a hand-lever, *F'*. The lower ends of the side pieces are connected with the platform-frame by means of connecting bars or links *f*. This frame *F*, with its lever *F'* and 25 the connecting-links *f*, forms one means for sliding the platform-frame on the binder-frame by taking hold of the lever *F'* and swinging the lever forward or backward as required to slide the platform-frame backward or forward. 30 Other means than this frame, lever, and links can be used for moving the platform-frame, and instead of making the lever *F'* a hand-lever it might be arranged as a foot-lever.

G is a segmental bar having openings or 35 notches *g* to receive a pin, *g'*, on the outer side bar of the frame, and hold the frame in any position in which it may be adjusted, so as to lock the platform-frame in any desired position; but other means can be used for this purpose.

H is the main or drive wheel, located on a shaft, *h*, which has its bearings *h'* located on the outer side piece *a*, and intermediate piece, *a*², of the main frame.

45 *I* is a gear-wheel located on the shaft *h*, and rotated by the main or drive wheel.

J is a pinion meshing with the gear *I*.

K is a shaft, on one end of which is secured the pinion *J*, which shaft has its bearings in 50 the intermediate frame-piece, *a*², and inner frame-piece, *a*, of the main or binder frame.

L is a beveled gear-wheel attached to the inner end of the shaft *K*.

55 *M* is a beveled gear-wheel meshing with the gear *L*.

N is a shaft, on the forward end of which is located the pinion *M*.

60 *O* are arms for supporting the shaft *N*, the forward one of which is attached to the inner piece, *a*, of the main or binder frame, so as to remain stationary, and the rear one of which is slotted or made in two parts, and attached to the intermediate cross-piece, *b*², of the platform-frame, so as to move with such frame.

65 *P* is a sprocket-wheel located on the shaft *N* between the rear supports, *O*, and attached

to such shaft so as to revolve therewith, and at the same time allow the shaft *N* to slide forward and backward, which attachment may be made by providing a groove in the 70 shaft *N* to receive a spline in the opening of the wheel *P*, through which the shaft passes.

Q is a drive-chain.

R is a sprocket-wheel, over which and the sprocket-wheel *P* the drive-chain *Q* passes.

75 *S* is a shaft having on its forward end a disk, *S'*, carrying a crank-pin, *i*, to which the inner end of the sickle is attached, and by means of which the sickle is driven. This shaft is supported in suitable bearings, *j*, located on the front and rear pieces, *b*, of the platform-frame.

80 *T* is a brace-rod attached at its forward end to the inner piece, *a*, of the main or binder frame, and extending back and passing through guides or bearings *k*, located on the front and rear pieces of the platform-frame, so as to be free to slide in such guides to allow the platform-frame to be adjusted fore and aft.

85 As shown, the rear end of the main or binder frame is supported by a caster-wheel, *l*, located in a frame or support, *m*, pivotally attached by a journal or pin, *o*, to a bracket, *n*, attached to the rear piece, *a'*, of the main or binder frame; but this end of the main or binder frame might be supported in some other manner, and the attachment of the caster-wheel could be made to the main or binder frame in some other place than to the rear piece, so long as the location of the caster-wheel is such as 90 to allow a free adjustment of the platform-frame on the main or binder frame, and as shown the grain end of the platform-frame is supported by a grain-wheel, *p*, which may be constructed and arranged in the usual manner.

95 The carrier is not shown, nor the devices for operating it; but it is to be located in the platform-frame and arranged to deliver the grain onto the receiving-table, where it is to be 100 bound; and it may be made of canvas provided with slats, or of chains provided with teeth, or in any other suitable and well-known form of construction.

105 The operation is as follows: The binder-frame has the binder supported thereon, so as to remain in a fixed position, and this frame also is fixed in relation to its supporting-wheels. When binding long grain, the secondary or platform frame is carried forward to the extent of its movement by the adjusting devices—either the lever and the frame *F* *F'* and connecting-links *f* or other devices—bringing the cut of the machine farther forward in relation to the binder, so that the grain as it is cut will 115 fall on the platform with its butts farther forward in relation to the travel of the binder-arm, and the band will be carried around the grain for the bundle farther back and at or near the center thereof. When binding medium grain, the platform is adjusted so as to bring it midway of the limit of its movement 120 125 130

fore and aft, so that the grain as it is cut will fall on the platform with its butts farther back in relation to the binder than for long grain, bringing it in position for the binding-arm to 5 encompass the bundle at or near the center.

When binding short grain, the platform is carried back to the extent of its movement by the adjusting devices, bringing the cut nearer to the binder, so that the butts will fall on the platform and the grain be delivered to the binder, to have the arm encompass the bundle at or near the center. The extremes of adjustment fore and aft will take in extremely long and extremely short grain, and the medium adjustment between these two positions can be varied to suit different lengths of medium grain and have the bundle encompassed by the binding-cord in the proper manner, so that by this arrangement the delivery of the grain to the 20 binder can be made irrespective of its length.

As shown, the main driving-wheel is located forward of the cut; but it could be located in line with or at rear of cut, the main frame inclosing the same, and the platform-frame being located with the drive-wheel between its sides or at rear, as the position of the wheel requires. This wheel is to be supported, as usual, to raise and lower the frame for the cut, and could be located outside of the main frame, 30 if desired.

The arrangement of the driving mechanism for the sickle and carrier on the platform-frame and the connection thereof with the main wheel can be changed to suit the form of 35 machine, whether front, center, or rear cut, and to suit the form and arrangement of the cutter and the grain-carrier in relation to each other and to the main wheel; but in all cases the arrangement must be one to allow the platform-frame to be moved bodily fore and aft, carrying with it the sickle and the platform.

What I claim as new, and desire to secure by Letters Patent, is—

1. The combination, with the main frame carrying a self-binder, of a platform-frame 45 connected to the main frame so as to slide thereon, whereby it may be adjusted fore and aft bodily on the main frame, substantially as described.

2. The combination, with the main frame 50 carrying a self-binder, of the platform-frame connected to the main frame so as to slide thereon, and a lever fulcrumed to the main frame and connected with the platform-frame, for adjusting the same fore and aft on the main 55 frame, substantially as described.

3. The combination, with the main frame and the platform-frame connected thereto so as to slide thereon, of the shaft journaled in bearings connected one to the main frame and 60 the other to the platform-frame, the sprocket-wheel connected to said shaft so as to slide thereon, the sickle-shaft on the platform-frame, and the sprocket-chain connecting said shaft with the sliding sprocket-wheel, substantially 65 as described.

4. The combination, with the main frame and the platform-frame adapted to slide thereon, of the brace T, extending from the platform-frame to and connected with the main 70 frame, substantially as described.

5. The combination of the main frame carrying the binding mechanism, the platform-frame connected thereto by clasps, and adapted to slide thereon, and supporting the sickle 75 and carrier, and the lever fulcrumed to the main frame and connected by links with the sliding platform-frame, substantially as described.

WILLIAM F. OLIN.
